UNITED STATES PATENT OFFICE

LOUIS W. RICE, OF NEW YORK, N. Y., ASSIGNOR TO BERNARD RICE'S SONS
INCORPORATED, A CORPORATION OF NEW YORK

DESIGN FOR A COCKTAIL SHAKER OR THE LIKE

Application filed October 24, 1932. Serial No. 45,533. Term of patent 7 years.

To all whom it may concern:

Be it known that I, LOUIS W. RICE, a citizen of the United States, and resident of New York, county and State of New York, have invented a new, original, and ornamental

Design for Cocktail Shakers or the like, of which the following is a specification, reference being had to the accompanying drawing forming part thereof.

The drawing is a perspective view of a cocktail shaker showing my new design.

The ornamental panels are repeated, being continued around the body of the container, and the small panels into which the oblong panels are divided are for the display of recipes.

I claim:

The ornamental design for a cocktail shaker or the like, as shown and described.

LOUIS W. RICE.
